UNITED STATES PATENT OFFICE.

ORLANDO SUMNER, OF LONDON, ENGLAND.

STEAM-GENERATOR.

1,109,483.

Specification of Letters Patent.

Patented Sept. 1, 1914.

Application filed November 18, 1912. Serial No. 732,109.

To all whom it may concern:

Be it known that I, ORLANDO SUMNER, a citizen of the United Kingdom of Great Britain and Ireland, and resident of 39 Victoria street, Westminster, London, England, have invented certain new and useful Improvements in Steam-Generators, of which the following is a specification, such as will enable others skilled in the art to which it appertains to make and use the same.

My invention has for its object to provide a completely self-contained steam generator which while receiving cold feed-water can economically deliver dry or super-heated steam without the assistance of extraneous economizers and superheaters, and more particularly has for its object to use a single steam and water drum and to provide an economizer or feed-water heater and chamber which form integral parts of the generator and are adaptable to water-tube boilers.

The effect of introducing comparatively cool feed-water into a generator under steam is to locally reduce the temperature of the water in process of evaporation and to condense certain of the steam generated, to overcome which the feed-water has hitherto generally been previously heated by extraneous economizers or feed-water heaters, which are either of great bulk and proportionate cost or absorb a considerable amount of the heat units required for steam raising.

In my invention the economizer forms an integral part of the generator and is so devised that the waste gases may be trapped before they enter the uptake and the feed-water thereby heated in a more economical manner than has hitherto been possible.

The triangular disposition of the three banks of tubes in my generator affords a suitable position for the integral economizer chamber between these banks of tubes, and as the aperture affording communication between this economizer chamber and the combustion chamber is disposed opposite to the outlet for the waste gases into the flue or uptake, it follows that there is no absorption by the economizer tubes of the heat required for steam raising, while the position of the economizer chamber assures that within it there is a greater heat than is available for feed-water heating in the uptake or flue; and this higher temperature in the economizer chamber assures the feed-water heating tubes inside it being immune

from the heavy soot and tarry deposits common to the use of any extraneous economizer, which it is known only begin to form at a temperature of about 600° Fahr. and increase as the temperature of the waste gases decreases. The employment of feed-water heating tubes in any part of a combustion chamber other than in the manner described in my invention obviously absorbs a large proportion of the heat units which would be better employed in steam raising.

The objections referred to are entirely overcome in my invention as will be seen from the following description and accompanying drawings forming a part of this specification, in which similar numbers of reference indicate like parts in both drawings.

Figures 1 and 2 are respectively a side sectional elevation and a front sectional elevation showing one of the forms in which the integral economizer may be conveniently employed without interference with the existing arrangements of the water-tubes and drums, the drawings showing it applied to my 3-drum generator. The baffle plates 1, 2 and 3 deflecting the furnace gases from the furnace to the uptake are of equal width with the combustion chamber, and by their disposition constitute walls forming the economizer chamber 4 and substantially enveloping the economizer tubes 5 which are transversely disposed across the combustion chamber 6. The lower extremity of the baffle plate 3 is shortened to provide the economizer chamber opening 7 which is situated immediately opposite the outlet 8 through which the products of combustion pass from the combustion chamber. The products of combustion sweep around the outside of the economizer chamber walls 1, 2 and 3 in the order named and are thus effectually prevented from contact with the economizer tubes until they are no longer required for steam raising, as the position of the aperture 7 assures that the economizer chamber receives only waste gases at a temperature in excess of that in the uptake or flue.

As shown in the accompanying drawings the economizer chamber is in the nature of a waste heat reservoir having any suitable outlet such as the outlets 25 which extend from the sides of the economizer chamber and lead to and communicate with the

smoke uptake. Feed-water enters the integral economizer at the bottom 9 and leaves it at the top 10, passing through the pipe 11 into the steam and water drum 12, down the 5 tubes 13 into the mud drum 14, up the tubes 15 into the water drum 16, and up the tubes 17 into the steam and water drum 12. The steam from drum 12 may be conducted through the pipe 18 into the integral su- 10 perheater 19.

The steam and water drum 12 is carried in the fixed chocks 20 on the frames 21, the water drum 16 is carried through the combustion chamber and supported in sliding 15 chocks which permit it to move freely under the influences of expansion and contraction only on the frames 23, and the mud drum 14 is suspended entirely by tubes from drums 12 and 16. To provide efficient 20 anchoring of the generator in its frames for marine use, drums 12 and 16 are provided with circumferential straps 24 in contact with the inner sides of their respective chocks, while the mud drum 14 has at either 25 end stoppers in contact with the frames which are not shown in the accompanying drawings. These provisions effectually prevent any undesirable movement of the generator proper while the general arrangement affords unusually ample provision for 30 expansion and contraction.

It is apparent that by extending or contracting the distances between the drums the amount of heating surface in the respective banks of tubes may be correctly proportioned to the heat value of the hot gases between the furnace and the uptake. It is equally obvious that a boiler of this general design must have a perfect circulation, one 35 that is positive, rapid, uniform, and certain in action locally as well as generally, obviating deposit or scale in improper places and permitting the use of feed-water highly charged with mineral salts in solution or im- 40 purities without risk or damage from deposit.

The accompanying drawings show the generator fired from the front, but it may

also be fired from either side and from the back.

50

What I claim and desire to secure by Letters Patent is:—

1. In combination with a furnace and the combustion chamber thereof, a steam generator comprising drums, tubes connecting the drums, an economizer supported between the drums, means for substantially housing the economizer, said means having an opening for admitting products of combustion to the economizer.

60

2. In combination with a furnace and the combustion chamber thereof, a steam generator comprising drums, an economizer associated with the drums, baffle plates substantially housing the economizer, said baffle plates being arranged to provide an opening, said opening adapted to admit products of combustion to the economizer substantially as described.

65

3. In combination with a furnace, a steam generator comprising drums, water tubes connecting the drums, an economizer chamber supported between the drums, an economizer supported in the chamber, said chamber having an opening arranged within the outlet of the furnace to admit products of combustion to the economizer for heating water held thereby.

70

4. In combination with a furnace and the combustion chamber thereof, a steam generator comprising drums, tubes connecting the drums, an economizer supported between the drums, means for substantially housing the economizer, said means having an opening for admitting products of combustion to the economizer, means of communication between the economizer chamber to the smoke uptake by inducing circulation through said economizer chamber.

80

In witness whereof I have hereunto set 90 my hand in presence of witnesses.

ORLANDO SUMNER.
